(57) CLAIM

The ornamental design for a purse organizer, as substantially shown and described.

DESCRIPTION

FIG. 1 is a front perspective view of a purse organizer, showing the novel design;

FIG. 2 is a rear perspective view of the purse organizer shown in FIG. 1;

FIG. 3 is a front elevational view of the purse organizer shown in FIG. 1;

FIG. 4 is a rear elevational view of the purse organizer shown in FIG. 1;

FIG. 5 is a top elevational view of the purse organizer shown in FIG. 1;

FIG. 6 is a bottom elevational view of the purse organizer shown in FIG. 1;

FIG. 7 is a side elevational view of the purse organizer shown in FIG. 1;

FIG. 8 is a side elevational view of the purse organizer shown in FIG. 1;

FIG. 9 is a top perspective view of the purse organizer shown in FIG. 1; and,

FIG. 10 is a front perspective view of the purse organizer shown in FIG. 1 with a front flap in an elevated or open position.

In an alternative embodiment of the current invention, one or more elongate pockets adapted to hold pens, pencils, and the like, said elongate pockets currently denoted as environment, are positioned adjacent to either of the two (2) elongate pockets adapted to hold pens, pencils, and the like, said two (2) elongate pockets currently denoted as claimed. In an alternative embodiment of the current invention, an expansion zipper, which is currently denoted as environment, is disposed along the bottom and each side of the purse organizer.

The dot-dashed broken lines showing the handles, portion of an envelope, pen compartments, cards, zipper and zipper pulls are for the purposes of illustrating environment and form no part of the claimed design.

The evenly spaced broken lines represent stitching and are part of the claimed design.
